UNITED STATES PATENT OFFICE.

GEORGE W. WELLS, OF SOUTHBRIDGE, MASSACHUSETTS.

DESIGN FOR A CYLINDER-LENS.

SPECIFICATION forming part of Design No. 35,769, dated February 25, 1902.

Application filed June 28, 1901; Serial No. 66,434; Term of patent 14 years.

To all whom it may concern:

Be it known that I, GEORGE W. WELLS, a citizen of the United States, residing at Southbridge, in the county of Worcester and State 5 of Massachusetts, have invented and produced a new and original Design for Cylinder-Lenses, of which the following is the specification, reference being had to the drawing forming a part thereof.

10 My invention relates to cylinder-lens such as is used in oculists' lens-cases and generally known and designated as "cylinder-lens."

Referring to the drawing, Figure 1 shows in perspective view a cylinder-lens embodying my design. Fig. 2 shows an edge view of the cylinder-lens shown by Fig. 1.

In the accompanying drawing, A represents a cylinder-lens having its surface α formed on the curve of a cylinder. The cylindrical

surface α' of the lens has two parallel broken 20 lines $a a$, as shown, the said broken lines being located near the opposite edges or portions thereof and at a distance from said edges. On one surface of the lens between the lines a arrow-heads b are formed to denote the central line or axis of the lens. 25

The leading or material feature of my design consists of a lens having a cylindrical surface and two broken lines arranged near opposite edges or portions of the lens and parallel to each other. 30

What I claim is—

The design for a lens substantially as shown and described.

GEORGE W. WELLS.
